AMUSEMENT DEVICE

Arthur B. Hall, San Dimas, Calif.

Application February 7, 1940, Serial No. 317,696

2 Claims. (Cl. 273—113)

This invention relates to amusement devices and more especially to puzzles.

An object of the invention is to provide a simple, inexpensive and entertaining puzzle of the character described.

Another object of the invention is to provide a puzzle of the labyrinth type in which certain objects are to be progressed from one point to another along a deviating path having a number of false branches.

A further object is to provide a puzzle having a multicellular structure wherein the path of progression leads from one cell to another.

An additional object is to provide a puzzle as described comprising a cube having a plurality of transparent walled cells having a labyrinth path therein for one or more objects such as balls.

Other objects and advantages will appear and be brought out more fully in the following specification, reference being had to the accompanying drawing, wherein:

Fig. 1 is a top view of a puzzle embodying my invention;

Fig. 2 is a front view of the same;

Fig. 3 is a bottom view of the same; and

Fig. 4 is an exploded view of the same.

Referring more particularly to the drawing, I show a container 5 preferably though not necessarily in the form of a cube having the usual side walls and a top 6 and a bottom 7, the sides, walls, top and bottom being preferably of any suitable transparent material. A pair of cross walls 8 and 9 are dovetailed with a pair of cross walls 10 and 11 at right angles thereto and are mounted on bottom 7 and support a plate 12 which may be considered to constitute a second stage, the bottom 7 being considered the first stage. Similarly a pair of cross walls 13 and 14 are dovetailed with a pair of cross walls 15 and 16 which together support a plate 17 constituting the third stage. In the same manner a pair of cross walls 18 and 19 are dovetailed with cross walls 20 and 21 and support a plate 22 comprising the fourth stage which in turn carries right angle cross walls 23, 24, 25 and 26 adjacent top 6.

Cross wall 8 has a pair of apertures 8a and 8c in the lower portion thereof and an aperture 8b in the upper portion thereof, and wall 9 has a plurality of apertures 9a, 9b and 9c in the upper portion thereof as shown. Similarly, walls 14, 15, 16, 18, 21, 23, 24 and 26 have one, two or three apertures therein in the upper or lower portions thereof as shown and designated in a similar manner. Walls 10, 11, 13, 19, 20 and 25 do not have any apertures.

Plate 12 has a plurality of apertures 12a, 12b, 12c and 12d as shown. Plate 17 has a plurality of apertures 17a, 17b, 17c and 17d. Similarly, plate 22 has apertures 22a, 22b, 22c, 22d, 22e, 22f and 22g. The structure as described thus com-

prises a cellular block having thirty-six cells which may be designated A on the first stage, B on the second stage, C and D on the third stage, and E, F, G, H, I, J, K, L, LL, M, N, O, P, Q, R, S, T, U, V, W, X, Y on the several stages as shown.

Cell A is provided with a suitable marker or indicia 27 which may be secured to bottom 7 if desired, and cells LL, M, W and Y are similarly provided with indicia 28 which may differentiate in

color or in any other manner from indicia 27.

Four small balls 29 are provided and the object of the game is to progress the balls, starting with all of them in cell A, through the apertured walls into and through the other cells until one ball is left in each cell LL, M, W and Y or over the indicia 28. It can be understood that the container 5 may be turned as may be necessary to permit the balls to drop through the wall apertures and the progression through the walls of

10 the puzzles is as follows:

Starting from cell A, the container is inverted, whereupon the balls fall through aperture 12b into cell B, then through aperture 17c into cell C. The container is then turned and the balls pass through aperture 18a into cell D, and in a similar manner into and out of the remaining cells E, F, G, etc., in alphabetical order. When cell L has been reached, one of the balls is manipulated into cell LL and the other three into cell M where 15 one is left, and the other two continued through aperture 12d into cell N and continuing until cell W is reached, one ball being then continued to cell Y which is the end of the labyrinth.

Having described my invention, what I claim is:

1. An amusement device as described, comprising a transparent closed container having a plurality of contiguous cells cubical in shape, a plurality of said cells being arranged in more than 20 one horizontal plane, there being apertures in a plurality of walls of said cells adapted to define an irregular passage from a predetermined cell to a second predetermined cell, and an object adapted to be progressed through said passage, a plurality of said apertures and cells adapted to define dead end branch passages.

2. An amusement device as described, comprising a hollow transparent closed container having a plurality of contiguous cells cubical in shape, there being apertures in a plurality of the walls of said cells, said apertures being arranged adjacent to or spaced from other walls of said cells in a predetermined manner, said cells and apertures adapted to define a labyrinth passage from a predetermined cell to a second predetermined cell, there being branch passages to a plurality of additional predetermined cells, and a plurality of objects adapted to be progressed through said
